UNITED STATES PATENT OFFICE.

WOJCIECH G. JAMROG, OF SAGINAW, MICHIGAN.

COAL-CAR SUPPORT.

Application filed October 5, 1922. Serial No. 592,640.

To all whom it may concern:

Be it known that I, WOJCIECH G. JAMROG, a citizen of the United States of America, residing at Saginaw, in the county of Saginaw and State of Michigan, have invented certain new and useful Improvements in Coal-Car Supports, of which the following is a specification.

This invention relates to new and useful improvements in supports for coal cars of either the wooden or metallic type, and has particular reference to that species of coal car support adapted to be positioned between the side walls of the car for preventing any outward bulging or breaking of the same due to the pressure of the coal there-

The primary object of this invention is the provision of such a support that is both simple and inexpensive of manufacture and a support that may be readily attached to cars in an expeditious manner and one wherein the same may be positioned upon coal cars of varying dimensions.

Other objects of the invention will become apparent as the nature thereof is better understood, and the same consists of the novel form, combination and arrangement of parts hereinafter more fully described, shown in the accompanying drawing and claimed.

In the drawing, wherein like reference characters designate corresponding parts throughout the several views,

Figure 1 is a side elevational view partly in section of my improved device showing the same attached to brackets carried by the side walls of the car, said side walls being shown in dotted lines,

Figure 2 is a top plan view of the same showing in addition thereto a means for readily operating the device for controlling the adjustability thereof when once installed in the car,

Figure 3 is a top plan view of a portion of the device, one of the elements being shown in both full and dotted lines,

Figure 4 is a side elevational view of the mechanism shown in Fig. 3 with one of the elements being disclosed in a removed dotted line position, and

Figures 5 and 6 are front elevational and top plan views respectively of a modified form of wall engaging clamp employed in the present invention.

Referring more in particular to the sev-

eral views there is disclosed in outline a portion of a coal car comprising side walls 1 and 2 and disposed diametrically opposite each other upon the inner faces of the said walls are inverted L-shaped bracket members 3 and 4. These bracket members are secured to the walls of the car by rivets 5 or the like and the upper longitudinal wall of the bracket member 4 is centrally apertured for receiving a vertically disposed pivot pin 6 for pivotally securing upon said horizontal wall of the bracket member the inner end of a screw threaded annular shaped rod 7, the bracket engaging end of this rod being flattened and of annular shape and also being centrally apertured for receiving said pivot pin.

The upper horizontally disposed wall of the opposite L-shaped bracket member 3 is provided with a centrally disposed key-shaped slot 8 for receiving one end of another annular shaped screw threaded rod 9. This bracket engaging end of the rod 9 is right-angularly bent as at 10 for defining a hooked portion 11 which has formed upon the end thereof an inwardly extending shoulder 12 for preventing disengagement of this screw threaded rod 9 from the key slot in the bracket 3 when the same is positioned as shown in Figs. 1 and 2. For positioning this rod 9 within the bracket the same is positioned as shown in full lines in Figs. 3 and 4 for allowing the hooked end thereof to pass through the slot, after which the same may be turned to be inter-connected with the opposite screw threaded rod 7 by means hereinafter more fully described.

As before stated, the rods 7 and 9 are screw threaded and it is to be herein noted that these screw threaded rods are detachably connected by means of a form of turn buckle denoted in general by the numeral 13. This turn buckle 13 may be of any desired form, but for purposes of illustration I have shown the same as comprising a casting having a central flattened portion 14 having formed thereon oppositely projecting side legs 15 and 16, these legs having a central longitudinally extending bore 17 the same being screw threaded for reception of the screw threads of the rods 7 and 9. It will therefore be seen that by engaging these rods within the screw threaded bores of the turn buckle 13 and by imparting a turning movement to the said turn buckle a rigid connection will be provided between the

ends of the rods. As a means for actuating the said turn buckle the flattened portion 14 thereof may be centrally apertured as at 18 for receiving an operating bar 19 shown in Fig. 2.

In Figs. 5 and 6 I have disclosed a slightly modified form of wall engaging bracket and it will be readily noted that these brackets include a central substantially rectangular 10 plate member 20 having inturned side flanges 21 formed thereon, these side flanges carrying oppositely extending ear portions 22 suitably apertured for receiving suitable securing means for attaching these brackets 15 to the walls of the car. In the preferred embodiment of my invention it is desirable that a plurality of these supports be positioned within each coal car and it is to be noted that the best results are to be procured 20 if these supports are positioned within the car preliminarily to the loading of the same with coal, but, however, should it be desired to fill the car with the devices in an inoperative position, the turn buckle may be so 25 manipulated as to disengage the same from the rod members 7 and 9 at which time the detachable rod 9 may be removed from its bracket for allowing the opposite rod 7 to

be swung upon its pivot 6 in which position the rod 9 may be advantageously secured 30 within the turn buckle and then supported upon the opposite rod 7 by screwing the turn buckle 13 thereon.

Minor changes may be made in the invention without departing from the spirit and 35 scope thereof as claimed.

What I claim is:—

In a support for coal cars, a pair of angular brackets carried by the inner walls of the coal car and positioned diametrically 40 opposite each other, a rod member carried by each of the brackets, one of said rod members being pivotally mounted upon its adjacent bracket and the other rod member being positioned upon its adjacent bracket 45 as to be detachable therefrom, and means for detachably connecting the opposite free ends of the said rod members, said rod members being screw threaded and adapted to receive a turn buckle connection at their 50 ends, the said detachable rod member being so formed at one of its ends as to prevent disengagement from its adjacent bracket when the two rods are interconnected.

In testimony whereof I affix my signature.
WOJCIECH G. JAMROG.
